CLAIM

The ornamental design for a candle holder set, as shown and described.

DESCRIPTION

FIG. 1 is a left front isometric view of a candle holder set showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view of the left shaker in FIG. 2, the right side view being a mirror image of that shown; and, FIG. 7 is a left side elevation view of the right shaker in FIG. 2, the right side view being a mirror image of that shown.

The broken line disclosure in the views are for illustrative purposes only and form no part of the claimed design.
